UNITED STATES PATENT OFFICE.

ANSON PHELPS STOKES, OF NEW YORK, N. Y.

CENTERBOARD.

SPECIFICATION forming part of Letters Patent No. 724,217, dated March 31, 1903.

Application filed October 20, 1902. Serial No. 127,921. (No model.)

To all whom it may concern:

Be it known that I, ANSON PHELPS STOKES, a citizen of the United States, residing at New York, county and State of New York, have invented certain new and useful Improvements in Centerboards, of which the following is a specification, reference being had to the drawings accompanying and forming part of the same.

10 My invention relates to centerboards for sailing vessels, and has for its object to provide means and mechanism for manipulating such devices with ease, safety, and precision. I am aware that many attempts have been 15 made heretofore to accomplish this end; but to the best of my knowledge the prior devices have not proved satisfactory. This failure was in many cases due to the complicated nature of the apparatus employed, for which 20 reason it was liable to get out of order. Sudden strains on the mechanism—as, for example, those caused by rough weather or heavy seas—were also liable to break some of the operative parts of the same, while the common device of lowering and raising the centerboard by means of a rope has been found 25 inefficient and unsafe where large or metal centerboards are used. My invention, however, is simple in construction, having few 30 members, and is such that the parts may be made of any desired strength. At the same time it is easily manipulated and the operator has complete control of the centerboard at all times.

35 Referring now to the drawings, Figure 1 is a vertical longitudinal section showing an embodiment of my invention. Fig. 2 is a section on line 2 2, Fig. 3; and Fig. 3 is a view similar to that of Fig. 1, but showing the centerboard in raised position.

40 Throughout the various figures, 1 indicates the centerboard-trunk, in which the centerboard 2, preferably of bronze, is pivoted at 3. On the pivoted or forward end of the centerboard is a segmental rack 4, cut through the edge of the centerboard, and bronze strengthening-pieces 5, secured on each side and surrounding the axle 3, as shown. Meshing with the segmental rack are two pinions 6 7, suitably journaled, bearing bevel - gears 8 9, which latter mesh with similar gears 10 on

vertical shafts 11 12, having hand-wheels 13 14 on their upper ends. The shafts or rods are preferably of bronze and so arranged that they may be raised or lowered, thus 55 throwing the bevel-gears into or out of engagement. By lowering the shafts and revolving the same by means of hand-wheels the pinions will be rotated and the position of the centerboard shifted as desired. To 60 limit the descent, a projection 15 is formed on edge of centerboard and strengthening-pieces 5, which presses against a bronze pin 16, extending through the centerboard-trunk when the centerboard has reached its lowest 65 position. A suitable spring or buffer may be provided to prevent jar or shock when the forward end of the centerboard moves against the pin.

70 The centerboard being secured to a strong and carefully-made shaft or axle, it is held rigidly against lateral movement, all rubbing and pressure on the inner sides of the trunk are avoided, and the lower part of centerboard when down is more securely held in 75 place. In order to further brace or strengthen the centerboard, the pinions may be provided with flanges 17, of any desired strength, extending down over the segmental rack to hold the same. A grooved block 18 may also 80 be used for the same purpose, placed between the pinions, with the rack moving in the groove. The axle is placed in position by driving it through the keel and centerboard from the outside. By mounting the centerboard firmly on an axle or shaft which itself rotates in suitable bearings, most of the strain 85 caused by lateral pressure on the centerboard, which strain in the old forms was supported by the trunk and much of it by the weakest 90 part of the sides of the trunk, is in my invention transformed into a vertical strain on the axle, which is carried by the keel and the strong adjacent parts—that is, pressure on the centerboard is changed largely to vertical pressure on the axle. This axle arrangement by making it possible to lower the centerboard much farther than in the old forms permits a shorter centerboard to be used to obtain the same or greater exposed surface. 95 It thus makes a better pivot for the vessel to go about on and permits a shorter opening in 100

the bottom to be used, and this opening can be made very narrow by screwing thereon a plate having a narrow slot in which the centerboard works.

5 From the foregoing it will be seen that my improved centerboard possesses certain advantages over those heretofore used, such as ease of manipulation, avoidance of pressure and wear on the trunk, and strength of construction. The weight of the strengthening pieces tends to balance the centerboard, and the strain on the hoisting apparatus is less and is more uniform. The construction is safer, stronger, better placed, and exposes a 15 larger surface below the vessel than the old type, and it permits the more convenient use of centerboards, and especially metal centerboards, with large vessels. The arrangement of the operating devices at the side of the 20 trunk instead of in line therewith presents an additional advantage in that it permits a central passage from cabin to gallery, &c., without the interference of a pipe for the centerboard pennant or rope.

25 While the form shown and described I regard as a convenient embodiment, it will be clear that the same is capable of many variations without exceeding the limits of my invention.

30 What I claim is—

1. The combination with a centerboard of one or more strengthening pieces secured on the same at its pivoted end, whereby the centerboard is to some extent balanced and a 35 strong connection afforded with the shaft on which the same is mounted, as set forth.

2. The combination with a centerboard of a segmental rack, on the pivoted or forward end, one or more flanged pinions meshing 40 with said rack and means for rotating said pinions, whereby the centerboard may be

raised or lowered, as and for the purposes set forth.

3. The combination with a centerboard, of a segmental rack, on the pivoted or forward 45 end, one or more pinions meshing with said rack, gearing for causing said pinions to rotate and means for actuating said gearing whereby the centerboard may be raised or lowered, as and for the purposes set forth. 50

4. The combination with a centerboard of a segmental rack, one or more pinions meshing with said rack, bevel-gears on said pinions, bevel-gears meshing with the first-mentioned gears, and means for rotating the last- 55 mentioned gears whereby the centerboard may be raised or lowered.

5. The combination with a centerboard, of a segmental rack, one or more pinions meshing with said rack, bevel-gears on said pinions, rotatable shafts bearing bevel-gears 60 engaging the first-mentioned gears, and means for rotating said shafts, as and for the purposes set forth.

6. The combination with a centerboard, of a segmental rack, one or more pinions meshing with said rack, bevel-gears on said pinions, rotatable shafts bearing bevel-gears 65 engaging the first-mentioned gears, and hand-wheels on said shafts for rotating the same, 70 as and for the purposes set forth.

7. The combination with a centerboard, having a segmental rack, one or more pinions meshing with said rack, and means for rotating said pinions whereby the centerboard may 75 be raised or lowered, of a grooved block adjacent to said pinions receiving the segmental rack, as and for the purposes set forth.

ANSON PHELPS STOKES.
